**METHOD AND APPARATUS FOR PREVENTING
MOISTURE ACCUMULATION IN TANKS**

Oscar C. Smith, Box 207, Newton, N.C.

Filed Jan. 17, 1958, Ser. No. 709,699

5 Claims. (Cl. 183—4.3)

This invention relates to a method and an apparatus for preventing moisture accumulation in a tank containing fluid, such as bulk transformer oil, fuel oil, gasoline, etc.

As is well known, transformer oil is commonly used as an insulating medium in electrical transformers. It has been determined that the infiltration of moisture into the transformer oil acts as a detriment to its insulating properties. The problem of moisture contamination is accentuated because a tank containing this transformer oil is normally vented allowing it to "breathe" as a safety precaution. This "breathing" of the tank prevents the build-up of excessive pressure within the tank such as might occur by the sun heating up the tank and causing the oil therein to greatly expand. Conversely, it is also necessary to prevent the build-up of an excessive vacuum condition within the tank which could be caused by the cooling of the transformer oil carried therein and its consequent contraction. The "breathing" of the tank is accomplished by nothing more than providing vent means for it wherein the pressure or lack of pressure within the tank will be adjusted to place the tank interior under a pressure in substantial equilibrium with the atmospheric pressure prevailing.

If "breathing" is allowed, whenever an excessive amount of pressure is present within the tank, the excess pressure bleeds off through the vent into the atmosphere to restore pressure equilibrium. Should a vacuum condition be present in the tank, atmospheric air is sucked through the vent into the tank to restore pressure equilibrium. Bulk transformer oil must, in most instances, be transported or shipped from areas of supply to areas of demand. In shipping such oil, a tank truck is commonly used as one mode of transportation. Whenever some form of long-range transportation must be used to deliver the bulk transformer oil to where it is needed, the "breathing" cycles of the receptacle containing the oil will be greatly multiplied owing to the extreme changes in temperature and atmospheric pressure encountered by the transporting vehicle as it travels from one region to another. During the vacuum stage of the "breathing" cycle of the tank, moist air from the atmosphere will be drawn into the tank to contaminate the transformer oil contained therein with water formed from the condensation of the moisture in the air and accordingly impair its insulating properties. The degree of moisture contamination is especially bad when the tank containing the transformer oil is transported through an area having a humid atmosphere.

In dispensing transformer oil from the tank, pressure is lost from the tank in the act of dispensing which again is likely to create a vacuum condition in the tank, resulting in moist air from the atmosphere being drawn into the tank during this stage of the "breathing cycle" to contaminate the transformer oil.

It is an object of this invention to provide a method and apparatus for maintaining a fluid, such as bulk transformer oil, contained in a vented tank free from moisture

2

contamination. The apparatus and method contemplate the introduction of air under pressure through a line containing a drying chamber and into the interior of the tank, whereby the tank interior is at almost all times maintained under a predetermined pressurized condition in excess of atmospheric pressure, thereby substantially preventing the intake of moist air from the atmosphere to avert the introduction of moisture into the tank.

It is a further object of this invention to provide a method and apparatus for preventing moisture accumulation in a vented tank containing fluid, such as bulk transformer oil, regardless of whether the pressure condition within the tank indicates an excessive pressure or a vacuum condition, in which a pair of air dehydrating units communicate with the interior of the tank and act conjointly to prevent the introduction of moisture into the tank, one such unit being effective when a pressure in excess of atmospheric pressure is to be maintained in the tank and the other unit being effective when a vacuum condition is present in the tank.

It is a further object of this invention to provide a method of dispensing fluid from a vented tank while preventing the accumulation of moisture therein, wherein dry air is admitted into the tank to preclude the occurrence of a vacuum condition therein caused by the loss of pressure involved when the fluid is dispensed, thereby eliminating the intake of moist atmospheric air by the tank.

Other objects not specifically enumerated will become more readily apparent upon reading the description in connection with the accompanying drawings in which—

Figure 1 shows a perspective view of a tank truck, in which the tank is equipped with the apparatus embodying the present invention;

Figure 2 is an enlarged fragmentary view, partially schematic, of the tank shown in Figure 1, with parts thereof being shown in vertical section;

Figure 3 is an enlarged vertical sectional view of the vacuum valve assembly shown in the upper left-hand portion of Figure 2;

Figure 4 is an enlarged vertical sectional view of the air filter component shown in the right-hand portion of Figure 2;

Figure 5 is an enlarged vertical sectional view of the pressure relief valve assembly shown in the upper medial portion of Figure 2;

Figure 6 is an enlarged transverse cross-sectional view of the drying chamber taken along line 6—6 in Figure 2.

Referring to the drawings more specifically, Figure 1 illustrates a truck 10 of the type carrying a tank 11, suitable for transporting fluids, such as gasoline, or as more particularly appropriate in this instance, bulk transformer oil. The tank 11 is provided with the usual fluid dispensing apparatus 12 attached to its rear end as shown in Figure 2. When transporting transformer oil in this manner, to be used as an insulating medium in electrical transformers, it is important to maintain the transformer oil moisture-free, since the presence of moisture is detrimental to the insulating properties of the transformer oil. The tank 11 is initially subjected to an extensive cleaning process in which all vestiges of moisture present in the tank are removed. Following this cleaning process, the transformer oil is introduced into the tank 11. It is the usual practice to vent the tank 11, permitting it to "breathe" should unequal pressure conditions prevail between the interior of the tank 11 and the atmosphere as a safety precaution. Should the tank 11 become heated thereby causing the transformer oil contained therein to expand, a greater pressure will exist in the tank as compared to that of atmosphere. Conversely, should the tank 11 be cooled,

70

the transformer oil contained therein will contract to decrease the amount of pressure within the interior of the tank, again resulting in an unbalanced pressure condition between the interior of the tank and the atmosphere. When the pressure differential between the interior of the tank 11 and the atmosphere exceeds prescribed limits, a dangerous situation is created which could lead to either the exploding or collapsing of the tank 11 as the case may be. For this reason, the tank 11 is commonly allowed to "breathe," thereby maintaining a substantially balanced pressure between its interior and the atmosphere at all times. While this "breathing" of the tank 11 is eminently successful as a safety precaution, it creates an additional problem of moisture contamination of the contents within the tank. When the tank 11 contains transformer oil, for example, its contamination by moisture is highly undesirable, for reasons previously described.

The present invention concerns itself with providing an apparatus and method for maintaining the contents of a vented tank moisture-free. It has been found that if the interior of the tank 11 is maintained under a predetermined positive pressure in excess of atmospheric pressure, the likelihood of moist air from the atmosphere being sucked into the interior of the tank is slight.

Referring again to Figure 1, it will be seen that a pair of dehydrating units 13 and 14 are carried on the tank 11. The apparatus or unit designated by reference numeral 13 is utilized to permit the introduction of air under pressure greater than atmospheric pressure into the tank 11 to maintain a predetermined pressure differential between the interior of the tank 11 and the atmosphere. The apparatus 13 is provided with means to relieve the compressed air of any moisture content prior to its introduction into the tank 11, as will be subsequently described.

A source of compressed air shown schematically in Figure 2 and designated by reference numeral 13a should be available in order to utilize the apparatus 13. This source of compressed air 13a may be mounted on the tank 11 in the form of a separate storage tank containing compressed air, but in most instances will comprise a compressor carried by the truck 10 and suitable for compressing atmospheric air, since the use of a separate storage tank for containing compressed air would add considerable weight and bulk to the load carried by the truck 10. It should be apparent that the compressed air could also be obtained from a source 13a entirely apart from any apparatus mounted on the tank 11 or carried by the truck 10. For example, it is likely that suitable means serving as the source of compressed air 13a would be found at a location where the fluid in the tank 11 is to be dispensed.

When the source of compressed air 13a is not available, the vacuum valve assembly or unit designated by reference numeral 14 is effective to prevent the moisture of the atmospheric air which may be drawn into the interior of the tank 11 from contaminating the contents therein. In the absence of the source of compressed air 13a, it is to be noted that dispensing the fluid from the tank 11 by means of the usual pump and nozzle arrangement 12 shown in Figure 2 will create a vacuum condition within the tank 11 as the fluid is withdrawn. Substantial pressure equilibrium between the interior of the tank 11 and the atmosphere is maintained by the vacuum valve assembly 14 which allows atmospheric air to be drawn into the interior of the tank 11, the moisture in the atmospheric air being withdrawn in the process, as is subsequently described.

In Figure 2, the vacuum valve assembly or unit 14 is shown as being mounted on the tank 11. The unit 14 includes a conduit 15 leading from the atmosphere to the interior of the tank 11. Interposed in the conduit 15, there is a vacuum valve 16 having a separate conduit

17 leading away therefrom to the interior of the tank 11. In order to prevent the continuous presence of moist atmospheric air in the conduit 15 above the vacuum valve 16, a damper valve 18 is positioned in the end of conduit 15 adjacent to the atmosphere. The damper valve 18 remains closed until a vacuum condition of a predetermined extent is created in the interior of the tank 11 either by the cooling thereof or by the dispensing of some of its contents, whereupon the damper valve 18 and the vacuum valve 16 will be opened to permit the ingress of atmospheric air into the conduit 15.

The vacuum valve 16 is of conventional structure, being shown in greater detail in Figure 3, and comprising a valve housing 20 having a pressure-responsive flexible diaphragm 21 extending within its interior to divide it into a pair of chambers. Above the diaphragm 21, there is positioned a spring 22 which contacts the upper surface of the diaphragm. Suitable means are provided for adjustably regulating the degree of compression in the spring 22 for varying the degree of vacuum condition required in the interior of the tank 11 to open the vacuum valve 16. Connected to the lower surface of the diaphragm 21 at its central portion, there is a rocker arm 23 for actuating a push rod 24 which extends through a valve seat 25. It will be noticed that the valve seat 25 is provided with a relatively wide bore therethrough with respect to the diameter of the push rod 24 which penetrates it to provide a passageway 26 for permitting atmospheric air to pass through the vacuum valve 16 should a vacuum condition of a predetermined extent exist in the tank 11. Normally the passageway 26 through the valve seat 25 is closed by means of a valve closure 27 which is spring-pressed against the valve seat 25. Atmospheric pressure is communicated through the conduit 15 into the interior of the valve housing 20 below the diaphragm 21. The pressure present in the tank 11 is communicated through the conduit 17 to the interior of the valve housing 20 above the diaphragm 21. It will thus be seen that should a vacuum condition of a predetermined extent be present in the tank 11, the atmospheric pressure below the diaphragm 21 is sufficient to overcome the compressive force of the spring 22 mounted above the diaphragm 21 and normally urging the central portion of the diaphragm 21 downwardly. When this occurs, the central portion of the diaphragm 21 is flexed upwardly, thereby moving the rocker arm 23 and the push rod 24 connected thereto, whereupon the push rod 24 unseats the valve closure 27 by moving it away from the valve seat 25 to permit the flow of atmospheric air through the passageway 26 in the valve seat 25 and downwardly therefrom into the conduit 15 leading toward the tank 11.

Upon passing through the vacuum valve assembly 16, the atmospheric air is conducted through a drying chamber 30 interposed in conduit 15 for relieving it of the moisture contained therein. The drying chamber 30 contains a desiccant or drying agent, such as calcium chloride or silica gel, indicated at 31 which effectively extracts the moisture content from the atmospheric air prior to its entrance into the tank 11. The drying chamber 30 preferably has wire mesh screens 31a installed above and below the drying agent 31 to retain it in place within the chamber 30.

When the source of compressed air 13a is available, unit or apparatus 13 is employed to maintain a higher pressure within the tank 11 than that existing in the atmosphere, whereby there will be little chance of atmospheric air being sucked through the unit or vacuum valve assembly 14 into the interior of the tank 11. Consequently the drying agent 31 in chamber 30 will be rarely called upon to extract moisture from atmospheric air passing through conduit 15 and will remain unsaturated for long periods of time without the necessity of constant checking. Referring to Figure 2 in describing unit 13, there is shown the source of compressed air 13a from which a conduit 32, preferably flexible, leads to a rigid

pipe 34, being connected thereto by a quick detachable connector 33 of conventional design. The usual pressure regulator 35 is installed in the pipe 34 to insure that the proper amount of pressure is being introduced into the tank 11. A pressure gauge 36 may be provided in the pipe 34, thus giving a visual indication of the pressure therein. Following the pressure gauge 36, an air filter chamber 37 of conventional design may be installed in the pipe 34 to remove foreign matter and the bulk of the excessive water and moisture from the compressed air prior to its entrance into a drying chamber 46 which removes the remaining vestiges of moisture from the compressed air.

The air filter 37 is shown in greater detail in Figure 4 and comprises an outer cylindrical casing or shield 40 which may be of transparent material and upper and lower end members 40a, 40b. In the lower end member 40b of the air filter 37, there is provided a stop cock 41 for removing the excess water from the air filter 37 when the compressed air is passed therethrough. It will be noted that as the compressed air enters the air filter 37 through pipe 34, it passes into outwardly diverging passageways 41a in the upper end member 40a of the air filter. The compressed air is thereby caused to swirl, allowing the bulk of the excessive water and moisture to be extracted therefrom, whereupon the excessive water falls to the lower end member 40b of the air filter 37 from which point it can subsequently be withdrawn by opening the stop cock 41. The swirling air then passes through an inner porous casing 42 spaced from the outer casing 40. Within the interior of the inner casing 42, there is a tubular conduit 43 having a plurality of apertures 44 therein. Once the compressed air has entered within the porous casing 42, it is permitted to pass through the apertures 44 and into the interior of the tubular conduit 43 from where it is led out of the air filter 37 into a continuation of the pipe 34.

The pipe 34 is suitably connected to a conduit 45, preferably flexible, and leading to the drying chamber 46. A cylindrical wire mesh enclosure or screen 47 is provided in the interior of the drying chamber 46 and contains a suitable desiccant or drying agent 50, such as calcium chloride or silica gel, which removes the remaining vestiges of moisture contained in the compressed air as it passes through the drying chamber 46 prior to its entrance into the tank 11. It will be noted that the drying agent 50 will be called upon to extract very small quantities of moisture, since the bulk of the same has already been removed from the compressed air by the air filter 37. Consequently, the drying agent 50 will remain effective to remove moisture from air passing therethrough for long periods of time without the necessity of constant checking.

From the drying chamber 46, the dry compressed air is led through conduit 51 into conduit 52 which leads to the interior of tank 11. Conduits 51 and 52 are suitably joined together, as by a T-coupling 53. Thus, the compressed air is permitted to enter into the interior of the tank 11 in a dry state to place the tank 11 under a predetermined pressure greater than atmospheric pressure. It has been found desirable to maintain a pressure of from two to four pounds per square inch in excess of atmospheric pressure in the tank 11. It will be seen, therefore, that when this excessive pressure condition is present in the tank 11, the possibility of moist atmospheric air being drawn into the tank 11 is eliminated.

Should a dangerous excess of pressure be built-up in the tank 11, such as might occur from the heat of the sun expanding the fluid contained therein, a pressure relief means 54 has been provided to allow the dangerous excess of pressure to be vented to the atmosphere. The pressure relief means 54 is mounted on the end of conduit 52 leading to the atmosphere and is shown in greater detail in Figure 5.

Referring to Figure 5 specifically, the pressure relief means 54 is in the form of a valve comprising a housing 55 having a pressure-responsive flexible diaphragm 56 extending within its interior to divide it into a pair of chambers. Above the diaphragm 56, there is positioned a spring 57 which contacts the upper surface of the diaphragm 56. Suitable means are provided for adjustably regulating the degree of compression in the spring 57 for varying the degree of excessive pressure required in the interior of the tank 11 to open the pressure relief valve 54. A valve seat 60 is provided below the diaphragm 56, said valve seat 60 having a passageway 61 formed therethrough leading from the interior of valve 54 to the atmosphere. Normally the passageway 61 through the valve seat 60 is closed by means of a closure plate 62 suitably connected to the lower surface of the central portion of diaphragm 56 and urged against the valve seat 60 by the spring 57. The pressure in the tank interior is communicated through the conduit 52 into the interior of the valve housing 55 below the diaphragm 56. It will thus be seen that should an excessive pressure condition of a predetermined extent be present in the tank 11, this excessive pressure is sufficient to overcome the compressive force of the spring 57 mounted above the diaphragm 56. When this occurs, the central portion of the diaphragm 56 is flexed upwardly, thereby moving the closure plate 62 connected thereto upwardly and away from the valve seat 60 to permit the dangerous excess of pressure in the tank 11 to pass through the passageway 61 into the atmosphere. When there is no longer any dangerous excess of pressure in the tank 11, the closure plate 62 again seats itself on the valve seat 60 to close the passageway 61.

It is to be understood that where the source of compressed air 13a is carried by the truck 10 or otherwise readily available, the unit or apparatus 13 is employed while dispensing the fluid from the tank 11 to introduce additional pressure into the tank 11 to at least partially compensate for the pressure which is lost in dispensing the fluid, it being desirable to continuously maintain a predetermined pressure within the tank 11 in excess of atmospheric pressure. The unit or apparatus 14 is used when there is no available source of compressed air to prevent the occurrence of a dangerous vacuum condition in the tank interior during the dispensing of the fluid by allowing atmospheric air from which the moisture has been removed to be drawn into the tank 11. Although this invention has been described with particular reference to maintaining bulk transformer oil moisture-free, it is contemplated that it may be utilized with tanks containing various types of fluids from which it is desirable to eliminate moisture contamination.

Thus, there has been described and illustrated an apparatus and method for preventing moisture accumulation in a vented tank containing fluid regardless of whether the pressure condition within the tank indicates an excessive pressure or a vacuum condition.

In the drawings and specification there has been set forth a preferred embodiment of the invention and, although specific terms are employed, they are used in a generic and descriptive sense only and not for purposes of limitation, the scope of the invention being defined in the claims.

I claim:

1. An apparatus for preventing the accumulation of moisture within a tank containing a fluid, said apparatus comprising a pair of dehydrating units, one of said units having a first conduit means for connection between a source of compressed air and the interior of the tank, a filtering means in said first conduit means for removing the bulk of moisture content in the compressed air, and air drying means in said first conduit means for extracting the remaining vestiges of moisture from the compressed air before it enters the tank, the other 70 of said units having a second conduit means for con-

nection to the interior of the tank and leading to the atmosphere, a vacuum valve assembly installed in said second conduit means, said vacuum valve assembly communicating with the interior of the tank and comprising normally closed valve means in said second conduit means operable in response to a predetermined vacuum condition within the tank to open, whereby air from the atmosphere may pass through said valve means in said second conduit means, and air drying means in said second conduit means for removing the moisture content from the atmospheric air before it enters the tank, whereby the tank will remain moisture-free regardless of whether an excessive pressure or a vacuum condition exists in its interior.

2. An apparatus for preventing the accumulation of moisture within a tank containing a fluid, said apparatus comprising a pair of dehydrating units, one of said units communicating at one end with a source of compressed air and at the other end with the interior of the tank, said one unit comprising means for removing the moisture content from the compressed air to permit it to enter into the tank in a dry state, the other of said units communicating at one end with the atmosphere and at the other end with the interior of the tank, said other unit comprising vacuum valve means normally closing off communication between the atmosphere and the interior of the tank and being operable in response to a predetermined vacuum condition within the tank to open for permitting the passage of air from the atmosphere therethrough, and means for removing the moisture content from the atmospheric air to permit it to enter into the tank in a dry state, whereby the tank will remain moisture-free regardless of whether an excessive pressure or a vacuum condition exists in its interior.

3. The combination with a tank having a vent therein of an apparatus for preventing moisture accumulation within said tank, said apparatus comprising means serving as a source of compressed air, means for removing the moisture content from the compressed air, and means to direct the dry compressed air into the tank for pro-

viding a pressure therein at least substantially equal to atmospheric pressure, the intake of moisture-laden atmospheric air by said tank through the vent therein being eliminated upon the tank pressure being maintained at least substantially equal to atmospheric pressure.

4. The combination with a tank having a vent therein of an apparatus for preventing moisture accumulation within said tank, said apparatus comprising means serving as a source of compressed air, means for filtering out the bulk of moisture content in the compressed air, additional means for removing the remaining vestiges of moisture from the compressed air, and means to direct the dry compressed air into the tank for providing a pressure therein at least substantially equal to atmospheric pressure, the intake of moisture-laden atmospheric air by said tank through the vent therein being eliminated upon the tank pressure being maintained at least substantially equal to atmospheric pressure.

5. A method of preventing moisture accumulation within a tank containing a fluid, comprising the steps of passing air through a line leading to the tank, filtering out the bulk of moisture content in the air at a first station by swirling the air to separate the moisture therefrom through centrifugal force and drawing off the centrifugally separated moisture from the air, extracting the remaining vestiges of moisture from the air at a second station prior to its entry into the tank, and directing the dry air into the tank to provide a pressure therein at least substantially equal to atmospheric pressure, whereby the intake of moisture-laden atmospheric air by the tank is eliminated.
